CLAMPING DEVICE

Hawley W. Lincoln, Hamden, Conn.

Application March 17, 1939, Serial No. 262,522

2 Claims. (Cl. 27—23)

The present invention relates to new and improved clamping devices.

The primary object of the invention resides in the provision of a clamp especially adapted for use by morticians to induce drainage of blood through a rubber tube and to effectively clean the same.

A further object aims to provide a clamp that can be freely moved along an extension of rubber tubing or the like to create a suction therein to induce complete drainage of a liquid and cause it to flow through said tube.

The invention will be fully and comprehensively understood from a consideration of the following detailed description when read in connection with the accompanying drawing which forms a part of the application.

In the drawing:

Figure 1 is a perspective view of the new and improved clamping device and illustrating the same in use.

Figure 2 is a transverse sectional view of the clamp and shown in its normal position, and

Figure 3 is a sectional view taken substantially on line 3—3 of Figure 2.

Referring to the drawing for a more detailed description thereof, the new and improved clamp generally designated by the reference numeral 5 comprises a pair of semi-elliptical shaped members 6 and 7, respectively, having formed on each side thereof ear portions 8 disposed in overlapping relation and receiving a stud 9 for pivotally supporting the members 6 and 7. It will be noted that the ear portions 8 are formed adjacent the rear end of the clamp and, in conjunction with the coiled tension spring 10 which encircles the stud 9 having arms contacting the inner surface of each of the members as indicated at 11, maintains the front end of the clamp in a normally open position. The rear faces 12 of each of the clamp members 6 and 7, respectively, simulate jaw members which are normally closed by the action of the spring 10 as more clearly shown in Figure 2 of the drawing.

The forward end 13 of the members 6 and 7 curve inwardly as indicated at 14 and in cooperation with the angular plates or brackets 15 form the means of supporting a pair of slightly concaved rollers 16. The brackets 15 are welded or otherwise secured to the inner face of the front end of each of the clamp members and form supporting means for one end of the trunnions 17 on which the rollers 16 are mounted, the other end of said trunnions being supported within the inwardly extending ends 14. The concave rollers

16, which are formed of any desired material, are preferably provided with a roughened tread-like surface as shown to prevent their slipping when moved transversely over a rubber tube or the like 18, and said rollers support and compress therebetween the rubber tubing 18 so that as the clamp is moved along the extension of the tube there will be formed a partial vacuum to induce drainage of blood from the body.

The outer surfaces of the forward end of the members 6 and 7 have a knurled portion 19 serving as a means for securely gripping the clamp when using the same. The normal position of the hand in use is shown in Figure 1 of the drawing with the thumb resting upon the upper member 6 and the fingers engaging the lower member 7 with the rubber tube securely gripped by the rollers 16 when pressure is exerted on the respective clamps.

When the device is used by a mortician for inducing the drainage of blood from a corpse, the metal drain tube which includes an extension of rubber tubing is first inserted in the vein and the clamp is positioned on the rubber tube at the point nearest the junction of the metal drain tube and the rubber tube. Pressure is then applied to the front end of the clamp and the concave rollers 16 will compress the portion of the tubing supported therebetween. The clamp is then moved toward the end of the tube forcing out any matter contained therein and at the same time setting up a partial vacuum which is sufficient to induce drainage of blood from the corpse. It is apparent that the concavity of the rollers 16 will maintain the tube centered with respect to the clamp at all times and at the same time provide efficient means for tightly compressing the tube to create the desired vacuum. By moving the clamp from the point nearest the junction of the metal drain tube and the rubber tube (away from the body) over the rubber tube several times flow of the liquid will be positively induced and at the same time there will be forced out any liquid within the tube.

While the present invention has been illustrated and described for use by morticians, it is to be understood that the same may be used as a means for positively and quickly creating a vacuum in a rubber hose or tube regardless of the nature of the liquid or from what point it is desired to induce a flow of liquid. By reason of the fact that the clamp is especially light in weight and easily handled, it provides an effective instrument for inducing the flow of any liquid when used as above described.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the invention nor exceed the scope thereof as expressed in the appended claims.

What is claimed is:

- 15 1. A clamp of the character described comprising, a pair of elongated semi-elliptical shaped members pivotally connected adjacent one end thereof, one end of said members defining a pair of cooperating jaws, a pair of concaved rollers

carried by said members adapted upon compressing said jaws to grippingly engage an article positioned therein, and means for normally maintaining said jaws in spaced relation.

2. A clamp of the character described comprising, a pair of elongated semi-elliptical-shaped members having ears formed adjacent one end thereof and disposed in overlapping relation for pivotally connecting said members, the forward end of said members being bent inwardly, a 10 bracket carried by each of said members and spaced from said forward end, a concaved roller carried by each of said brackets and said forward end and adapted upon compressing said members to grippingly engage an article positioned therebetween, and means for normally maintaining said rollers in spaced relation.
